CLAIM

The ornamental design for a sterilizable air purifier, as shown and described.

DESCRIPTION

FIG. 1 is a front elevational view of the first embodiment of a sterilizable air purifier showing our new design;

FIG. 2 is a right side view thereof;

FIG. 3 is a left side view thereof;

FIG. 4 is a top plan view thereof;

FIG. 5 is a bottom plan view thereof;

FIG. 6 is a top and right perspective view thereof; and,

FIG. 7 is a bottom and left perspective view thereof.

A rear elevational view of the first embodiment of the sterilizable air purifier is omitted since the rear elevational view thereof is a mirror image of the front elevational view thereof.
